Patented Apr. 27, 1920.

UNITED STATES PATENT OFFICE.

FRANCISCO HERNANDEZ Y PEREZ, OF HABANA, CUBA.

LUBRICATED HINGE.

1,338,251.

Specification of Letters Patent. Patented Apr. 27, 1920.

Application filed March 22, 1919. Serial No. 284,230.

To all whom it may concern:

Be it known that I, FRANCISCO HERNANDEZ Y PEREZ, a citizen of the Republic of Cuba, residing at Habana, Cuba, have invented new and useful Improvements in Lubricated Hinges, of which the following is a specification.

This invention relates to an improved form of hinge and aims to more particularly 10 provide a device of this nature, which will require a minimum of attention and be very noiseless in operation.

Attention is invited to the attached sheet of drawings in which—

15 Figure 1 is a side elevation of the entire hinge;

Fig. 2 is a section taken along the line A—B of Fig. 1;

Fig. 3 is a side elevation of the left hand, 20 or weight carrying portion of the hinge;

Fig. 4 is a side elevation of the right hand or supporting portion of the hinge;

Fig. 5 illustrates the construction which 25 renders my device noiseless and easy in operation; and

Figs. 6 and 7 are end views of the devices illustrated in Figs. 3 and 5.

In these drawings, 1 designates the leaf of the weight carrying portion of the hinge, 30 and 2 the similar portion of the opposite half of the hinge, both of said leaves being provided with the usual counterbored openings 3 for the reception of screws or other suitable securing means. The weight carrying, or left hand portion of the hinge is 35 provided with lugs 4 and 5 formed with openings 6 positioned adjacent its upper and lower edges respectively.

The opposite leaf 2 has formed along its 40 side edge a cylindrical casing 6' provided with shoulder portions 7 adjacent its edges.

The casing 6' houses a rod 8 provided with a bore 9, such rod being provided with a shoulder portion 10 at its upper end. It 45 will be noted that the lugs 4 and 5 and the shoulder portion 10 are further provided with an opening 11, as illustrated in Figs. 2, 6 and 7.

The rod 8 has formed in its lower face recesses 12, into which lugs 13 of a disk 14 project, such disk 14 being further formed with an annular groove 15 in its lower face.

A cap 16 is positioned within the lower end of the casing 6' and projects beyond the 55 same, as shown in Fig. 2, said cap being secured to the casing by means of the screw

17. The cap 16 is further formed with an annular groove 18 and interposed between the lower face of the disk 14 and the upper face of the cap 16 is a second disk 19 formed 60 with ball races in its upper and lower faces, housing ball bearings 20.

A headed pin 21 projects centrally through the disks 19 and 14 and the rod 10, terminating at a plane above the upper face 65 of the lug 4. It will be noted that the head 22 of such pin is provided with a cut out portion 23, adapted to receive a spike 24 projecting through the openings 11 in the lug 4 and the rod 10, also that the rod is so 70 formed as to permit of the existence of an annular space between its outer face and the inner face of the cylindrical casing 6', such space being adapted to receive any suitable lubricating material. 75

In operation it will now be seen that upon the leaf 2 being secured to the jamb and the door being affixed to the leaf 1, that downward pressure will be exerted upon the lug 4, such lug bearing upon the shouldered 80 portion of the rod 10, which turns therewith, said rod transmitting in turn the weight to the disk 14 and the ball races 20, thus throwing all the weight upon the ball bearings, resulting in easy motion of the 85 door. It will be further noted that the disk 14 is positively movable with the rod 10, which in turn is secured to the leaf 1 by means of the opening 11 in the lug 4. The disk 19 revolves idly about the pin 21 and 90 the cap 16 is fixed to the leaf 2 by means of the screw 17 projecting through the cylindrical casing 6', thus rendering the same immovable.

It will be understood that various modifications may be resorted to, as for instance, the disk 14 being integral with the rod 10 and a second opening 11 being provided through the lug 5 and shoulder of the cap 16, so that the hinge may be reversed. 95

Having now described my invention 100 what I desire to claim is:—

1. A hinge including a pair of leaves, one of said leaves being provided with lugs adjacent its upper and lower edges, and the second leaf being formed with a cylindrical casing adjacent one side edge, a rod secured to the upper lug to turn therewith, said rod projecting into and being spaced from the cylindrical casing, ball races positioned below the lower end of the rod, said ball races including a disk secured to the lower end of 105 110

the rod to turn therewith, a base portion below said lower end, a disk positioned between the first named disk and base portion, and bearing balls interposed between said latter disk, the base portion and the first named disk, and a pin, extending centrally through said upper lug, said rod and said disks.

2. A hinge including a pair of leaves, one of said leaves being provided with lugs adjacent its upper and lower edges, a second leaf being formed with a cylindrical casing adjacent its side edge, a rod secured to the upper of the lugs to turn therewith, such rod projecting into and being spaced from the cylindrical casing, and a ball bearing for the lower end of said rod and in said casing.

3. A hinge including a pair of leaves, one

of said leaves being provided with lugs adjacent its upper and lower edges, the second leaf being formed with a cylindrical casing adjacent its side edge, a rod secured to the upper of the lugs to turn therewith, such rod projecting into and being spaced from the cylindrical casing, ball races positioned below the lower face of the rod, such ball races including a disk secured to the lower face of the rod to turn therewith, a base portion below such lower face, a disk positioned between the first named disk and base portion, and bearing balls interposed between such latter disk, the base portion and first named disk.

FRANCISCO HERNANDEZ y PEREZ.
